TOILET ACCESSORY

Henry Josephs, New York, N. Y.

Application June 23, 1941, Serial No. 399,325

4 Claims. (Cl. 242—55.5)

This invention relates to improvements in toilet accessories, and more particularly an accessory for dispensing tissue in combination with lipstick or similar material, and is an improvement of my co-pending application S. N. 354,121, filed August 24, 1940, issued as Patent Number 2,275,183 March 3, 1942.

Objects

Among the principal objects which the present invention has in view are:—to provide an improved toilet accessory for dispensing tissue in combination with lipstick or the like; to provide a toilet accessory having means for dispensing tissue therefrom at any suitable length; to provide frictional means for engaging tissue being dispensed from the toilet accessory; to provide actuating means for dispensing tissue from the toilet accessory; to provide a toilet accessory having means whereby new rolls of tissue may be inserted in the accessory; to be enabled to sever strips of tissue and advance the tissue as desired; to provide a clockwise motion for dispensing tissue from the toilet accessory; to provide a cap on the toilet accessory rotatable in one direction; to provide a cap having means for actuating frictional means within the toilet accessory when dispensing tissue therefrom; to provide a hinged closure having means for temporarily locking the same when in closed condition; to secure simplicity of construction and operation; and to obtain other advantages and results as may be brought out in the following description.

Drawing

Figure 1 is a vertical elevation view of one part of the improved toilet accessory;

Figure 2 is a similar view and showing another part of the accessory;

Figure 3 is a view similar to Figure 1 and showing the hinged closure in open position with a roll of tissue indicated in dot and dash lines inside the accessory;

Figure 4 is a vertical sectional view shown as taken on line 4—4 of Figure 2;

Figure 5 is a cross-sectional view shown as taken on line 5—5 of Figure 1;

Figure 6 is an enlarged fragmentary sectional view of the upper part of the accessory; and

Figure 7 is an enlarged view of the underside of the rotatable member and partly in section shown as taken on line 7—7 of Figure 6.

Description

As seen from the drawing, the several figures

are particularly directed to a construction whereby a tissue may be dispensed and severed at any desired length when required, and when a desired strip has been severed the edge remaining within the accessory will be in readiness for progressive ejection therefrom. The accessory in construction is somewhat similar to that shown in my co-pending application S. N. 354,121, filed August 24, 1940, insofar as it consists of a tubular body member 10, to which may be attached at the underside a lipstick or rouge receptacle 11 having a removable closure cap 12. The combined tissue dispenser and lipstick receptacle as shown is somewhat exaggerated in size for purposes of illustration, and in actual use may be of a standard size and shape whereby a user can conveniently place it in a purse or other carrying agent and not requiring excessive space when not in use.

Referring now more particularly to the several figures illustrated in the drawing, the tubular body member 10 may be constructed of any suitable shape, such as round, square, octagon and so forth, and may be of a material such as metal or plastic and/or other suitable material. For purposes of illustration the device is tubular and comprises two semi-cylindrical sections A and B, and is provided at its lower end with a lipstick or rouge receptacle 11, secured thereto as by a rivet 13 and by virtue of this rivet is free to rotate with respect to the tubular body member 10. When a user desires to use the lipstick or rouge contained within the receptacle, the closure cap 12 conveniently may be removed therefrom and replaced after use.

The tubular body member 10 and particularly the section A, preferably may be provided at its upper part with a top wall 14 and at its bottom with a bottom wall 15 thereby providing a hollow interior. A roll of facial tissue 16 shown in dot and dash lines in Figures 2, 3 and 5 may be inserted in the body member 10 and as it is entirely dispensed may be replaced with refills.

An opening 17 extending approximately the distance of section A is provided and extends the full length from the top wall 14 to the bottom wall 15 thereby permitting easy insertion of the roll of tissue 16 into the interior of the said section. Section B for clarity may be a closure 18 for the opening of Section A as by being hingedly secured thereto as at 19 with the hinge portion extending the entire longitudinal length of the tubular body member and allows for opening and closing of the closure as

desired. Said closure 18 at its longitudinal edge opposite the hinged portion conveniently may be provided with a serrated edge 20 against which the exposed portion of the tissue 16 outside the accessory contacts and under influence of slight pressure thereagainst a strip of the tissue of any desired length may be severed from the main part of the tissue within the accessory. After a strip of tissue has been severed the part it has been severed from remains in alignment with the serrated edge 20 within the accessory until another strip is desired to be severed.

In order to facilitate progressive movement of the tissue from within the accessory, the body portion of section A at its end opposite to the hinged end preferably may be provided with an inwardly directed semi-cylindrical wall 21 extending downwardly from the top wall 14 to the bottom wall 15. The open portion of said semi-cylindrical wall 21 preferably faces the interior of the closure 18 of the section B when said closure is in closed condition. An elongated frictional roller may be provided within the confines of said semi-cylindrical wall and preferably extends the entire length of the wall. A portion of said roller extends slightly outward of the wall and in actual practice frictionally engages the tissue and progressively advances the tissue out of the accessory.

For retaining the closure 18 in closed or locked condition with respect to the section A, the closure 18 adjacent its upper and lower ends and centrally thereof is provided with inwardly projecting flat springs 22 having detents 23 therein. The upper and lower walls 14 and 15 respectively each are cut away to provide openings 24 of a size to accommodate reception of the spring members 22. Adjacent the inner edges of said openings upraised portions 25 are provided and as the closure operates to close the opening of section A the spring members slide in the openings 24 and raise slightly when coming in contact with the upraised portions 25. The detents 23 will then frictionally engage the upraised portions and the closure will then be in locked condition. Only slight pressure need be exerted for releasing the closure from its locked condition with respect to section A.

For progressively advancing the tissue 16 from the interior of the accessory there may be provided on the top of the tubular member and spaced slightly above the top wall 14 thereof a knurled cap 26 of a diameter substantially that of the combined sections A and B and preferably having a closed top and open on its underside, as clearly shown in Figures 6 and 7. Centrally and on the underside of the top of said cap and preferably integral therewith, may be provided with a downwardly extending stem 27, having an enlarged portion 28 providing gear teeth 29. A reduced shank portion 30 extends downwardly beyond the gear portion 28 and may be of a length sufficient to retain the cap spaced from the top wall 14 of the tubular member and provides a shoulder 31 resting upon said top wall. A further reduced shank 32 integral with gear portion 28, shank 30 extends downwardly through the top wall 14 with the lower end pressed or punched outwardly to engage the underside of the said top wall thereby making the cap and the several correlated members a part of the accessory and at the same time allowing the cap to be rotated. In order that the cap be not rotated too freely a coil spring 33 may be provided to encircle the shank 30 with the loose end of said spring ex-

tending downwardly through an opening 34 in the top wall. This loose end protruding into the interior of the accessory may then be bent slightly to prevent accidental withdrawal from the accessory. The relationship of the fixed shank 32 and loose spring portion to the top wall 14 allows rotatability of the cap 26 in only one direction or more specifically in clockwise direction. The frictional roller 35 rotates under influence of an elongated shaft 36 extending therethrough from the interior of the cap 26 with its lower end secured in the bottom wall 15. The upper end of the shaft in the cap may be provided with a reduced gear 37 the teeth of which are in mesh with the gear teeth 29 of portion 28.

In operation and when desiring to progressively advance tissue outward from the accessory and from between the roller 35 and serrated edge 20 of the closure 18, the user starts turning the cap 26 in a clockwise direction. In so doing the larger gear 28 rotates in the same direction of movement of the cap which in turn meshes with the teeth of gear 31 and rotates the same in a counter-clockwise direction as indicated by the arrows in Figure 7. As the gear 37 rotates opposite to that of the larger gear the frictional roller 35 by virtue of the shaft 36 will likewise rotate in counter-clockwise direction. Due to the fixed end of coil spring 33 in the top wall 14 the cap cannot be rotated in a counter-clockwise direction. From the foregoing disclosure it is to be noted the closure member 18 preferably may be slightly offset at the serrated edge portion away from the roller thereby providing a slight space from top to bottom of the tubular member. It is through this space the tissue may progressively advance under influence of the frictional roller 35 engaging the tissue as the cap is turned in clockwise direction.

Obviously other detail changes and modifications may be made in the construction and use of my improved toilet accessory without departing from the spirit and scope of the invention, and I do not wish to be understood as limiting myself to the exact construction or operation shown or described except as set forth in the following claims.

I claim:

1. A toilet accessory adapted to be carried on the person comprising a body portion for a roll of tissue, said body portion constituting an elongated substantially symmetrical casing concentric to a longitudinal axis and said body portion having an opening at its side substantially the size of the tissue roll for insertion of the roll sidewise therethrough, a friction roller eccentric to and lengthwise of said body portion, exterior means concentric with respect to said body portion for rotating said friction roller, and a closure for said opening of the body portion, said closure being movable in closing the same toward said friction roller into close proximity thereto by which in closing the same said closure grips the out-going portion of the tissue between the closure and said friction roller, whereby the tissue is situated to be fed and rotation of the roller feeds the tissue along the closure surface.

2. A toilet accessory adapted to be carried on the person comprising a body portion for a roll of tissue, said body portion constituting an elongated substantially symmetrical casing concentric to a longitudinal axis and said body portion having an opening at its side substantially the size of the tissue roll for insertion of the roll sidewise therethrough, a friction roller eccen-

tric to and lengthwise of said body portion next an edge of said opening, exterior means concentric with respect to said body portion for rotating said friction roller, and a closure for said opening of the body portion, said closure being hinged remote from said edge of the opening having the friction roller next thereto, said closure being swung in closing the same toward said friction roller into close proximity thereto and engaging the out-going portion of the tissue between said closure and roller, whereby the tissue is situated and engaged to be fed and rotation of the roller feeds the tissue along the closure surface.

3. A toilet accessory adapted to be carried on the person comprising a body portion for a roll of tissue, said body portion constituting an elongated substantially symmetrical casing concentric to a longitudinal axis and said body portion having an opening at its side substantially the size of the tissue roll for insertion of the roll sidewise therethrough, said body portion having an outwardly opening depression longitudinally next one edge of said opening, a friction roller within and lengthwise of said depression and eccentric with respect to the body portion and separated from the tissue roll by the body-portion wall forming said depression, exterior means concentric with respect to said body portion for rotating said friction roller, and a closure for

5 said opening of the body portion, said closure also overlapping said depression and in being closed is brought into engagement with the out-going portion of the tissue for gripping the tissue between said closure and friction roller, whereby the tissue is situated to be fed and rotation of the roller feeds the tissue along the closure surface.

10 4. A toilet accessory adapted to be carried on the person comprising a body portion for a roll of tissue, said body portion constituting an elongated substantially symmetrical casing concentric to a longitudinal axis and said body portion having an opening at its side substantially the size of the tissue roll for insertion of the roll sidewise therethrough, a friction roller eccentric to and lengthwise of said body portion, means for rotating said friction roller, said means comprising a cap concentric to and exterior of said body portion at one end thereof and overlying the end of said roller, a gear on said roller within said cap, and gear teeth in said cap meshing with said gear for rotating the roller, and a closure for said opening of the body portion cooperating with said friction roller for receiving the out-going portion of the tissue between the roller and closure as the closure is closed and for feeding the said tissue as said cap is rotated and the rotation imparted to said friction roller.
